(57) **CLAIM**

The ornamental design for a waterproof hang case for electronic device, as shown and described.

DESCRIPTION

FIG. 1 is a front, top, and left perspective view of waterproof hang case for electronic device, showing the claimed design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a front, bottom, and left perspective view thereof; and, FIG. 9 is a cross-sectional view taken along line 9-9 shown in FIG. 2.

The long dash short dash broken lines and arrows shown in FIG. 2 are used to identify the cross-sectional view and form no part of the claimed design. The evenly spaced broken lines shown in FIGS. 1 and 9 depict environment and form no part of the claimed design.

1 Claim, 8 Drawing Sheets
